UNITED STATES PATENT OFFICE.

CLARENCE E. BILTON, OF BRIDGEPORT, CONNECTICUT, ASSIGNOR TO THE STANDARD MANUFACTURING COMPANY, OF BRIDGEPORT, CONNECTICUT, A CORPORATION OF CONNECTICUT.

MILLING-MACHINE.

1,061,973.

Specification of Letters Patent.

Patented May 20, 1913.

Application filed April 17, 1911. Serial No. 821,695.

To all whom it may concern:

Be it known that I, CLARENCE E. BILTON, a citizen of the United States, and resident of Bridgeport, in the county of Fairfield and State of Connecticut, have invented certain new and useful Improvements in Milling-Machines, of which the following is a specification.

This invention relates to new and useful 10 improvements in milling machines and more particularly to a slotting machine, whereby slots of different width, depth and length can be automatically produced, in disks, plates, screws or other parts.

15 The particular object of my invention is to improve upon a commercial form of milling machine whereby it will be better adapted for special work, as for instance of radially slotting round metal plates such as 20 are employed upon knitting machines, or for the slotting of other forms or parts as for instance the heads of machine screws, and finally to simplify, cheapen and generally improve the construction of machines of this 25 class whereby they may be made to take in a larger variety of work and be constructed at a comparatively small cost.

The invention further consists in certain 30 novel features of construction and arrangements of parts through which the above objects are obtained, as will be more fully understood from the accompanying drawings, forming a part of this specification, upon 35 which similar characters of reference will be found to designate like or corresponding parts throughout the several figures and of which—

Figure 1, is a side elevation of my improved form of milling machine complete 40 as seen from the left of the front of the machine. Fig. 2, is a plan view of the machine shown in Fig. 1 though drawn on a slightly smaller scale and having a few of the unimportant features omitted as for instance the oil pump and its connections. Fig. 3, is a central vertical cross sectional view of the machine as taken on line 3—3 of Fig. 2. Fig. 4, is a detail plan view of a pawl and ratchet mechanism for indexing the rotary 45 table and work carried thereby, to be slot- 50 ed. Fig. 5, is a detached plan view of one of the knitting machine ring plates partially slotted as produced by my improved ma- 55 chine. Fig. 6, is an enlarged plan view of a modified form of rotary table with a

special form of holding device for retaining screws while being slotted. Fig. 7, is a detail side edge view of a part of the said rotary table showing one of the screw holding slides in end elevation, and Fig. 8, is a 60 detail longitudinal cross sectional view of a portion of the rotary table including a holding slide and punch for throwing the said screws out.

The main driving mechanism and operating connections of this machine, are very similar to that shown in my allowed application for patent on improvements in gear cutting machines Serial #890,460.

The feature of novelty herein, includes 70 changes of construction made necessary to adapt the machine for the special work heretofore referred to, and which I will later describe in detail, after briefly describing the method of construction and operation of 75 the necessary driving mechanism for operating said novel mechanisms.

Referring therefore to the numerals of reference marked upon the drawings 10 represents a bench upon which the machine is 80 mounted the same having a top inclined toward an oil pot 11 arranged beneath. Upon the bench is arranged the machine proper which includes a bed 12 supported upon short legs. A bracket 13 is secured to 85 the rear of the side portion of this bed and serves to support a worm shaft 14 connected by a clutch 15 with the driving pulleys 16. A worm gear 17 mounted upon a cam shaft 18 meshes with and is driven by the worm 90 on the worm shaft. The cam shaft 18 is suitably journaled in bearings 19 secured to the top of the rear portion of the bed and upon it is mounted four cams 20, 21, 22 and 23. The first mentioned two of these cams 95 are designed to operate the mechanism for successively rotating and locking the rotary table in position while the cams 22 and 23 serve to guide the cutter wheel across and into the work as will later be described. 24 100 represents a heavy bracket secured to the right hand side of the machine and which is provided with ways to receive a slide 25, the rear end of which is provided with an adjustable block 26 that bears a roll to engage 105 the cam groove of cam 23 for the purpose of reciprocating the slide backward and forward as occasion requires to draw the cutter through the work. A vertically operating head 27 is slidably mounted upon the for 110

ward end of the slide and is normally held in a raised position by means of springs 28 seated in the head and upon the forward end of the slide.

5 A bearing 29 is adjustably mounted in the face of the head 27 and is adapted to be raised or lowered by means of an adjusting screw 30. This bearing serves for the main spindle 31 that is provided with pulleys 32 upon one end and a cutter 33 upon the other end for operating upon the work. A lever 34 is pivoted to a bracket 35 and has its rear end in engagement with and is operated by a cam 22 while its forward end is provided 10 with an adjustable pin 36 that engages an adjustable block 37 secured to the head 27 that carries the bearing, spindle and cutter. The said cam 22 thus serves to operate the lever to press down the head, cutter, etc., 15 against the action of the springs 28 as for the purpose of making a deeper cut.

20 A rod 38 mounted in suitable bearings on the bed of the machine is connected to operate the clutch 15 before mentioned. A spring 39 seated upon this operating rod serves to hold the clutch in a disengaged position, but is held in engagement by a trip lever 40 also pivoted to the bed and designed to be tripped by the engagement therewith of a lug 41 on the rotary table 42. In the forward end of the bed is secured a bearing 43 having a central vertical hole therethrough for the reception of the vertically disposed spindle 44 that carries the 25 work carrying table.

30 A ratchet wheel 45 is secured to the lower end of the spindle 44 and is designed to be successively operated by a pawl 46 pivotally mounted upon an arm 47 hinged upon a collar 48 secured to the spindle. The arm 47 is thrown backward and forward by the cam 20 which directly acts upon the vertically disposed slide 49 that has a bevel face side which serves to engage and operate the 35 connecting rod 50 against the action of spring 51. The forward end of this rod is connected with the arm 47 carrying the pawl to engage the ratchet wheel.

40 In addition to the foregoing described mechanism for operating the ratchet wheel and its rotary table I provide a holding stop 52 that is slidably mounted in brackets secured to the underside of the bed and has its opposite end in engagement with a second vertical slide 53 that is manipulated by the cam 22 mounted upon the cam shaft, and is provided with an inclined edge that engages a pin on outer edge of slideable holding stop. A spring 54 serves to normally hold 45 this stop in a forward position and in engagement with a tooth of the ratchet wheel during the cutting operation while the cam serves to withdraw the stop when it is desired to turn the same forward in position 50 for further operation.

From the foregoing it will be seen that the ratchet wheel and its table may be operated step by step for the successive cutting operation, and that the said table is positively locked during the said cutting operations, and that when the table makes a complete rotation its lug 41 will strike the lever 40 and release the rod that frees the clutch and stops the machine. I also provide additional means for stopping the rotary table 70 with the completion of its rotary movement which consists in providing a hole in the underside of the table into which a spring 28^a actuated stop pin 55 is forced when the hole is brought into registration with the said pin. The pin is slidably mounted in the bed of the machine and connected with a lever 56 that is pivoted to a stud secured to the under side of the bed.

75 In order to release the table and allow it to rotate, the outer free end of the lever is pressed down to withdraw the pin from the table, against the action of its spring in a manner to allow the table to be started on its turning operation.

80 The work to be slotted is obviously carried upon the table which as before stated is successively rotated so as to move the same step by step to bring the work forward to receive the respective cuts. If the work to be operated upon is a plate or ring 57 such as is shown on the machine in Fig. 3 and in plan view in Fig. 5, I elect to hold it in position by means of an expandible split ring 58 seated against the inside of the plate and having an inner beveled edge against which a tapered clamp 59 is seated and held by means of a screw 60 see Fig. 3. Thus it will be seen that this plate can readily be released by simply loosening the screw and allowing the ring 58 to retract and relieve the said plate 57 when completed, and another blank set in place to be similarly operated upon.

85 If the machine is to be used for slotting the heads of screws and the like, a slightly different form of rotary table is required, that is, one having a suitable series of pockets and clamps therein to receive the screws to be operated upon. Such a form of modification is shown in Figs. 6 to 8 inclusive, and wherein the table 42 is provided with a series of radial slots 61 forming ways to receive a fixed die 62 and a slideable clamp 63. Beneath this clamp and in a pocket of the table is seated a spring 64 that is arranged intermediate of the shoulder in end of pocket of the table and a lug 65 on the slide. This spring thus arranged tends to normally draw the clamp out, leaving a suitable space, in the slot between the die and clamp to receive and loosely carry a screw 68 when placed therein. A block 66 is secured to the bed 12 of the machine beneath the cutter wheel and serves to support a 90

compressible spring 67 against which the ends of the clamps 63 abut and by means of which the said clamps are forced inward against the screws 68 when placed therein, 5 and for the purpose of clamping and holding the screws when the cutter is run through the head thereof. The screws are placed in the respective slots in the table and between the dies and clamps while the 10 table is in operation, and are securely held between said dies and clamps by the pressure of the spring as a result of the end being drawn in against the spring and at such times as when the screw or die is positioned 15 beneath the cutter. The movement of the pawl and ratchet wheel with each operation would be just sufficient to move the table shown, $\frac{1}{16}$ of a turn which is equal to that of the distance between the clamps. After 20 the screws have been slotted as shown in Fig. 6, they are moved forward a couple of stations and thus brought immediately above a punch 69 seated in the end of a lever 70 that is pivoted to a bracket 71 secured to the bed and connected to be operated by the cam 21^a.

From the foregoing it will be seen that, with each movement of the table a slotted screw is brought immediately over the punch, and that during the slotting operation, upon another screw, the lever is operated by the cam 21^a in a manner to cause the punch to knock out such finished screw thus leaving the pocket free to have another screw placed therein while the table is moving around.

Having thus described my invention what I claim and desire to secure by Letters Patent is—

40 1. In a milling machine of the class described, the combination with a rotary cutting tool, of a bed, a driving shaft, a vertical spin-

dle mounted in the bed, a pawl and ratchet for intermittently rotating the spindle, a connecting rod beneath the bed and connected with the pawl for operating the ratchet, a 45 vertical slide operated by the driving shaft to manipulate the said rod, a slideable holding stop also arranged beneath the bed and adapted to engage the ratchet, a vertical slide operated by the driving shaft and adapted to operate the holding stop to secure the ratchet in position, a horizontally arranged work carrying table mounted on the spindle, and means for securing the work 50 in position upon the table. 55

2. In a milling machine of the class described, the combination with a rotary cutting tool, of a bed, a driving shaft, a vertical spindle mounted in the bed, a pawl and ratchet for intermittently rotating the spindle, a spring actuated horizontal slide beneath the bed and connected with the pawl for operating the ratchet, a vertical slide 60 operated by the driving shaft to manipulate the said slide, a spring actuated slideable holding-stop also arranged beneath the bed and adapted to engage the ratchet, a vertical slide operated by the driving shaft and adapted to operate the holding-stop to secure the ratchet in position, a rotary work carrying table mounted on the spindle and having a hole therein, a spring actuated stop pin to engage the table and having an operating handle for its withdrawal, and means 65 for securing the work in position upon the table. 70 75

Signed at Bridgeport in the county of Fairfield and State of Connecticut this 11th day of April A. D., 1911.
